[57] CLAIM

The ornamental design for a hammer tip, as shown and described.

DESCRIPTION

FIG. 1 is a perspective view of a hammer tip according to the invention;

FIG. 2 is a top view of the hammer tip shown in FIG. 1;

FIG. 3 is a cross-section taken at line 3—3 in FIG. 2;

FIG. 4 is a bottom view of FIG. 2;

FIG. 5 is a side view of the hammer tip, with the opposite side view being identical; and,

FIG. 6 is an end view of the hammer tip, with the opposite end view being identical.
